MACHINE TOOL

Herbert Füssenhäuser, Augsburg, Germany, assignor to Maschinenfabrik Augsburg-Nürnberg A. G., Augsburg, Germany, a corporation of Germany

Application November 29, 1938, Serial No. 242,976
In Germany November 29, 1937

3 Claims. (Cl. 51—184.3)

This invention relates to machine tools and more particularly to tools for finishing or grinding grooves on the inside of a hollow part.

One object of the invention is the provision of a finishing or grinding tool having a series of surfacing or grinding members which are movable in substantially radial directions in a body member and having means for equalizing the outward pressure exerted on the individual surfacing members.

Another object of the invention is the provision of a finishing tool for finishing grooves on the inside of a hollow part and comprising a body member having a series of independently adjustable carriers on which the surfacing members are arranged, independently adjustable slides being provided to move the carriers differentially in substantially radial directions in the body member.

Another object of the invention is the provision of a surfacing tool of the character mentioned, in which the surfacing members are of substantially the same width as the width of the grooves to be surfaced or polished, the surfacing members being pivotally supported on their respective carriers for movement about axes substantially transverse of the longitudinal axis of the body member, for finishing inclined or helical grooves.

Other objects and advantages of the invention will be apparent from the following description, the appended claims, and the accompanying drawing, in which:

Fig. 1 is a longitudinal central section through a finishing tool embodying the present invention;

Fig. 2 is a transverse section on the line 2—2 of Fig. 1; and

Fig. 3 is a diagrammatic illustration of the pressure equalizing connection to the various slides.

Referring more particularly to the drawing by reference numerals, the finishing tool of the present invention comprises a shank 1 to which is screwed a shell 2, the shell enclosing a ball bearing 3 which provides balls on opposite sides of an end disk 4 which is secured to the body member 5 of the tool by means of a nut 6. The body 5 of the tool is thus capable of rotation with respect to the shank 1, and which provides for axial reciprocatory movement of the body 5.

Within the body 5 of the tool and secured thereto by means of a pin 7 is a guide rod or bolt 8 upon which a number of slides 9 are arranged, the slides 9 being positioned annularly about the

guide bolt and extending radially and capable of endwise movement on the guide bolt. They are held against turning on the guide bolt by means of a guide box 11 in which the end portions of the slides are slidably positioned. The guide box 11 is secured to the bolt 8 by means of pin 10.

The slides 9 are adapted to be moved by means which applies equal pressures to the various slides, such means as herein shown comprising a cable or string 12 which is carried over rollers or pulleys 13 arranged on the various slides 9 and rollers 14 which are carried by a spring pressed sleeve or pressure member 16. The ends of the cable 12 are connected to the pressure member 16 by means of a screw 15. Pressure member 16 is actuated by means of a spring 18 which bears at one end against a thrust plate 17 adjustably threaded on the pressure member 16 so that the tension of the spring 18 may be varied. The pressure member 16 is guided for axial movements on the bolt 8 and is held against rotation on the bolt by means of a pin 19 the opposite ends of which are slidable in slots extending axially in the pressure member 16.

Spring 18 at its opposite end presses against a part 20 which is secured as by means of screw threads to the end of the body member 5. This part 20 also serves to hold a guide ring 22 fast on the body member 5, a disk or washer 21 being provided between the part 20 and the guide ring. The cable 12 is arranged over the rollers or pulleys 13 and 14 in a zig-zag relationship so that when the pressure member 16 is moved to the left, see Fig. 1, by the spring 18, an equalized tension prevails in the various parts of the cable and equal pressures are applied to the several slides 9, thus yieldingly urging them towards the left axially of the bolt 8 with equal forces. The force applied to the slides 9 may be adjusted by turning the thrust plate 17 on the pressure member 16.

Fixed at the opposite end of each of the slides 9 is a threaded pin 23 which extends freely through annular disk 25. A nut 24 is threaded on each pin 23 on the outer side of the disk and the disk bears on a flange provided on a large nut 26 which is adjustably threaded on the body member 5. A key or wedge 27 holds the disk 25 against rotation on the body member 5 but permits axial movements of the disk. When the nut 26 is moved outwardly on the body member, or unscrewed, the disk 25 is moved to the right to the position indicated in Fig. 1, and the various slides are pulled positively to their normal retracted positions against the tension of the

spring 18. When the nut 26 is turned in the opposite direction the disk 25 is moved to the left and then separates from the nuts 24 so that the slides 9 may be moved differentially by the spring 18.

Each slide 9 cooperates with a carrier 28 which carries a surfacing member or grinding stone 32 preferably of rectangular form. The several carriers are slidably arranged and guided for axial movements in the body member 5. On each slide 9 there is a pair of inclined camming surfaces cooperating with correspondingly arranged camming surfaces on the respective carrier 28 so that as the slide 9 is moved axially to the left as viewed in Fig. 1, the carrier 28 is moved radially outward in the body member. Expansible ring springs 29 extend around the various carriers 28 and yieldingly restrain radially outward movements of the carriers and return them to their inner positions when the slides 9 are in their normal retracted positions.

The surfacing members or polishing stones 32 are mounted on holders 31 which are rotatably or pivotally mounted on trunnions 30 provided on the carriers. The width of the grinding stones 32 conforms to the width of the grooves to be finished in the inside of the hollow part in which the grooves to be finished are arranged, and since the stones can turn about the axis of the trunnions 30, it is possible to polish or finish 30 helical or inclined grooves as the stones may adapt themselves to the angularity of the grooves in the grooved part.

The tool is adapted to grind or finish a number of grooves on the inside of a hollow part and although the depth of the grooves may vary to some extent, and even if the depth of a groove or grooves is different at different points along its length, the finishing or accurate grinding or polishing of all the grooves may take place simultaneously since the carriers adapt themselves individually and differentially to grooves of different depths and apply equal radial forces to the work. In accordance with prior arrangements, the shallower grooves of a grooved part must first be ground down to a depth equal to the deeper grooves before the finishing operations on the deeper grooves can be started even though the depths of the unfinished grooves may not vary from a desired or correct measurement in excess of the limit of tolerance. Thus a very accurate machining or prefinishing operation has been necessary so that the grooves may be all of exactly the same depth before the finishing operation is started or else a very large amount of 50 close or final finishing has been required. It will be seen however that in accordance with the present invention, the individual carriers on which the surfacing members are independently arranged are relatively adjustable in radial directions but with equal outward pressures so that the close finishing of all of the grooves may proceed simultaneously without regard to the depth in the different grooves.

In a finishing operation the tool, which is fastened to a suitable reciprocating driving arbor, is introduced into the work, with the various slides in their retracted or normal position and held so against the action of the spring 18 by the

nut 26. The entry of the tool into the hollow body is facilitated by means of the guide ring 22, the entering end of which is suitably tapered. The grinding stones 32 are then released by turning the nut 26 on the body member, thus permitting the spring 18 to exert a predetermined and adjustable force on the various pulleys or wheels 14, which move the various slides 9 axially, thus forcing the several carriers 28 radially outward until the grinding stones engage the bottom surfaces of the grooves. The movement of the various carriers and their respective operating slides differs from one another if the depth of the various grooves is not uniform, although the pressure exerted by the several carriers is the same. All of the grooves in the work are therefore simultaneously finished or ground as the driving arbor is reciprocated. After the finishing operation has been completed, the slides 9 are retracted by unscrewing the nut 26, permitting the carriers 28 to be retracted by means of the expansible ring springs 29 so that the tool can then be readily removed from the hollow body.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A finishing tool of the character described for finishing grooves on the inside of a hollow part, comprising a body, a series of carriers adjustable independently of one another in said body for substantially radial movement therein, each carrier having a plurality of inclined camming surfaces, an axially movable slide for each of said carriers slidably carried by said body and having camming surfaces for moving its respective carrier outwardly when the slide is moved axially in one direction, spring means for moving all of said slides in said one direction, and means for equalizing the forces applied by said spring means to the several slides.

2. A finishing tool of the character described for finishing grooves on the inside of a hollow part, comprising a body, a series of carriers adjustable independently of one another in said body for substantially radial movement therein, an axially movable slide for each of said carriers for individually adjusting the carriers radially of the body, a pressure member operable axially of the body, and a cable connecting said pressure member to the various slides and having pressure equalizing connections therewith.

3. A finishing tool of the character described comprising a body, a series of carriers adjustable independently of one another for substantially radial movement in said body, an axially movable slide for each of said carriers and operably mounted in said body for adjusting the carriers substantially radially in the body, a spring, means interconnecting said spring and the several carriers to equalize the pressures exerted by said spring on said carriers, and means adjustable to positively move said slides against the action of said spring.

HERBERT FÜSSENHÄUSER.
